US00D653818S

(12) **United States Design Patent**
Schetlin et al.

(10) **Patent No.:** **US D653,818 S**
(45) **Date of Patent:** **** Feb. 7, 2012**

(54) **ANIMAL DRYER APPARATUS**

(76) Inventors: **Raymond M. Schetlin**, Myrtle Beach, SC (US); **Kimba M. Schetlin**, Myrtle Beach, SC (US)

(**) Term: **14 Years**

(21) Appl. No.: **29/349,158**

(22) Filed: **Mar. 12, 2010**

Related U.S. Application Data

(63) Continuation-in-part of application No. 12/006,863, filed on Jan. 7, 2008, now abandoned.

(51) **LOC (9) Cl.** **30-99**

(52) **U.S. Cl.** **D30/158; D30/199**

(58) **Field of Classification Search** **D30/158, D30/199; 119/678, 174, 677, 517-530, 796, 119/14.9, 14.03, 14.04, 606, 712, 416, 482, 119/500, 51.01, 62, 61.54; 43/127; 34/202, 34/201, 90, 93**

(57) **CLAIM**

The ornamental design for an animal dryer apparatus, as shown and described.

DESCRIPTION

FIG. 1 is a front perspective view of an animal dryer apparatus showing my new design;

FIG. 2 is a right side view thereof;

FIG. 3 is a left side view thereof;

FIG. 4 is a front view thereof;

FIG. 5 is a rear view thereof;

FIG. 6 is a top plan view thereof; and,

FIG. 7 is a bottom plan view thereof.
